UNITED STATES PATENT OFFICE.

LEE D. CRAIG, OF SAN FRANCISCO, CALIFORNIA.

PLUG STOP-VALVE.

SPECIFICATION forming part of Letters Patent No. 274,724, dated March 27, 1883.

Application filed February 6, 1883. (No model.)

To all whom it may concern:

Be it known that I, LEE D. CRAIG, a citizen of the United States, residing in the city and county of San Francisco, State of California, have invented a new and useful Improvement in Plug Stop-Valves, of which the following is a specification.

My invention is an improvement in plug stop-valves.

- 10 The object of the invention is to provide a simple and effective plug-valve adapted to be operated either by hand or, under certain conditions, automatically, to allow the escape of water or other liquid.
- 15 The invention consists in the general construction and arrangement of the various parts, all of which are hereinafter described, and the novel features of the invention pointed out in the claims.
- 20 In the accompanying drawings, Figure 1 is a central vertical section of the plug and its seat. Fig. 2 is a plan view of the same, and Fig. 3 is a side elevation of the complete device represented as attached to and operating 25 within a tank.

The plug (represented at A) is hollow, with a closed bottom and a truncated cone-shaped wall provided with openings O on opposite sides, for a purpose hereinafter explained. 30 Across the open top of the plug extends a piece, C, which supports a thimble or socket, E, referred to again. A seat, B, of similar tapering form to the plug A, is made in the sink or other receptacle in which the plug-valve is 35 to be used, and is adapted to receive such plug, which fits snugly therein. The seat is provided with openings O', on opposite sides thereof, similar to the openings in the plug, with which they register. The openings in 40 the seat may connect with a discharge-pipe direct; or they may empty into a chamber below the bottom of the receptacle surrounding the outside of the seat, and the contents of the receptacle be carried off from thence.

45 In order to operate the plug by hand, I have provided a key-rod, F, which has a square or polygonal end adapted to a similarly-shaped socket, D, in the bottom of the thimble E, before mentioned. The key may be made larger 50 above this socket to fit a correspondingly-enlarged opening, which tends to give support to the key when being operated. The key is provided at its upper end with a cross-bar or other suitable form of handle. It will be seen,

therefore, that by turning this handle the openings in the plug and seat may be made to register to discharge the contents of the receptacle in which the device is used, and after such discharge a half-turn of the handle will close the openings, when the key may be removed 6 from the socket in the plug and be put away for future use.

To provide a device by means of which the plug may be made automatic in its operation is another part of my invention, and this I have shown in Fig. 3. When automatically operated the openings in the plug are not utilized, but the discharge of the contents of the receptacle effected by the elevation of the plug clear off its seat. For this purpose I have provided the lever G, one end of which is pivoted to the wall of the tank, as at I. It is connected to the flange K of the plug by a yoke, J, which does not interfere with the operation of the device by hand. On the other end of the lever G, I place a float marked H. It is obvious from this construction that as the contents of the tank or other receptacle rise therein it will float the part H, and consequently lift the plug from its seat, when the contents 8 may escape. As the contents are discharged the float will fall with them and finally close the opening.

Of course it is obvious that this device may be used in tanks, sinks, bath-tubs, basins, and in all receptacles where water is collected and discharged.

Having thus described my invention, what I claim is—

1. The combination, with a sink or similar receptacle, of a plug adapted to close the discharge-pipe, a pivoted lever, G, connected thereto, and a float, H, whereby the valve of the plug is automatically raised to permit the water in the sink to escape, substantially as described.

2. The combination of the plug A and its seat (said plug being provided with a socket, E, adapted to receive a key) with the pivoted lever G, a float for automatically operating the same, and the yoke J, whereby the valve can be operated automatically or independently by hand, substantially as described.

LEE D. CRAIG. [L. S.]
